(57) **CLAIM**

We claim the ornamental design for a lockout device, as shown and described.

DESCRIPTION

FIG. 1 is a front perspective view of a lockout device of the new design;

FIG. 2 is a rear perspective view of the lockout device of FIG. 1;

FIG. 3 is a top view of the lockout device of FIG. 1;

FIG. 4 is a left side view of the lockout device of FIG. 1;

FIG. 5 is a right side view of the lockout device of FIG. 1;

FIG. 6 is a bottom view of the lockout device of FIG. 1;

FIG. 7 is a rear view of the lockout device of FIG. 1;

FIG. 8 is a front view of the lockout device of FIG. 1;

FIG. 9 is a front perspective view of a lockout device of the new design, wherein the unclaimed cup portions of the lockout device are larger than the lockout device of FIG. 1;

FIG. 10 is a rear perspective view of the lockout device of FIG. 9;

FIG. 11 is a front perspective view of a lockout device of the new design, wherein the unclaimed cup portions of the lockout device are smaller than the lockout device of FIG. 1; and,

FIG. 12 is a rear perspective view of the lockout device of FIG. 11.

The portions of the Figures shown in broken lines are for illustrative purpose only and form no part of the claimed design.

The shade lines adjacent to the broken lines define the bounds of the claimed design. The broken lines form no part of the claimed design.
